J. E. CROMWELL, OF JACKSON, MICHIGAN.

Letters Patent No. 66,569, dated July 9, 1867.

IMPROVEMENT IN MACHINES FOR FORMING WAGON-AXLES.

The Schedule referred to in these Letters Patent and making part of the same.

TO ALL WHOM IT MAY CONCERN:

Be it known that I, J. E. CROMWELL, of Jackson, in the county of Jackson, and State of Michigan, have invented a new and improved Lathe for Turning Wagon-Axles; and I do hereby declare that the following is a full, clear, and exact description thereof, reference being had to the accompanying drawings, forming part of this specification.

The nature of this invention relates to a machine for turning wagon-axles, or the arms of axles that run in the wheel, and consists in the combination of saws and cutters that work in conjunction with each other in forming and giving the proper shape to the arm of the axle. It also consists in the novel arrangement of the feed-works, or gauge, which operates against a pattern, which is duplicated by the machine in the most accurate and precise manner. For heavy wagon-work this machine is peculiarly adapted, and may be used to great advantage and profit. It is well known that to fit up the arm of a wagon-axle is a slow and laborious process, and the want of a machine for doing this work has been for a long time felt; and it is believed that by my invention a great and valuable labor-saving machine has been produced, and one that does its work with far greater accuracy and perfection than can possibly be done by hand.

To enable others skilled in the art to make and use my invention, I will proceed to describe its construction and operation.

Figure 1 is a top plan view of my improved lathe.

Figure 2 is a longitudinal vertical elevation, with the side of the frame removed from the line X X.

Letters of like name and kind refer to like parts in each of the figures.

A represents a frame made of wood, of any suitable dimensions and strength to support all the machinery of my improved lathe. B is a shaft, provided with journals that run in suitable bearings, secured to the posts of the frame A. Upon this shaft B is a large driving-band wheel, C, over which a belt, a, passes, and works over a small pulley, b, upon the shaft D. Upon this shaft D are also two long drums or pulleys E E, over which belts F F pass, and work over the pulleys upon the saw-shafts H H, fig. 2, that drive the cutters and saws I I'. Upon the said shaft D are two small pulleys J J'. A belt passes over the pulley J and works over a large pulley, K, that is secured to the screw feed-shaft L, that moves the guide or gauge-wheels M M along the pattern N, that revolves on pivots O O. Over the pulley J', which is secured to the shaft D, is a belt that passes and works over the pulley R, which is made fast to the outer end of the shaft Q. Upon this shaft Q is also another pulley P, over which a belt passes and works over the pulley S, the shaft of which runs in bearings, secured to the pendent or hinged frame T. On the shaft of the said pulley S and within the frame is a small pinion, W, that meshes into and drives two corresponding pinions or gear-wheels Y Y, upon the respective shafts of which are chucks that hold the pattern N and the work to be made. I I are the cutters, that are firmly secured to the collar of the saw, that follow upon the outside of the saw, and smooth the work after it has been formed by the saw. T is a frame hung by a hinge at one end to the main frame A. This said frame T is made to rise up and down, and yield to the action of the guide or gauge-rollers M, as they pass over the sinuosities of the pattern. A² is a frame to which are attached the saws and cutters I I'. The said frame A² is moved laterally across the frame A on gibs and slides B² B², the slides being attached to the pieces C² C² of the frame A. This frame A² is moved by means of two lever-nuts D² D², upon the end of which are weights E² E², for the purpose of bringing down the levers and engaging the nut with the screw-shaft L, and may be held in this position by the latch F², which, when in this position, feeds the saws and cutters to the work. G² G² are weights suspended by a cord, H², that passes over the pulleys I² I², and connects to the frame A². These weights are for the purpose of drawing back the saws and cutters after having passed over the work, and the nuts D² released from the shaft; the cutters are then immediately drawn back.

The operation of this lathe is simple, rapid, and perfect, and consists in placing the block of an axle O² into the chucks of the lathe, and applying any power to the shaft B at the crank P², when the whole machine is put in motion, and through the medium of the drums E E and belt F great speed is imparted to the saws and cutters I; and through the medium of the pulley J' R P and S, a proper motion is imparted to the pattern N and axle-stock O² and feed frame A², which is moved by the screw-shaft L. It will be here observed that the gauge-wheel can be set at any desired point on the shaft e by means of a screw-thread on the said shaft; and

when the frames A² are drawn by the weights G² up to the side of the frame A, the gauge-wheel should be set so as to come directly at the end of the pattern; and when the screw-shaft has fed the frame A², which contains the gauge-wheel and cutters, to a proper distance, as far as desired, the weights E² upon the end of the lever D are allowed to drop down, which disengages the nuts from the shaft, when, by the action of the weights G² G², the frames A² A² are drawn back and ready for another stock. It will again be noticed that the frame T is hinged at one end, which contains the pattern, and stock rests on the gauge-wheel M; and both the axle-stock and pattern having the same motion in their revolutions, and the same vertical motion, the stock is brought in contact with the saws and cutters so as to precisely correspond with the pattern.

I am aware of the patent granted to Newton J. Glover, dated May 25, 1858; Smith Beers, December 3, 1850, and June 6, 1854; T. Clark, January 19, 1847, and reissued November 12, 1850; but these have no relation to my improvements, and I do not therefore claim them. I am also aware of the patents granted to T. Blanchard, September 6, 1819, and T. Dennington, January 26, 1864, and August 14, 1866; but these I do not claim.

Having thus described my invention, what I claim as new and desire to secure by Letters Patent is—

The arrangement of the pendent-frame T, containing the gear-wheels Y Y and W, pattern N resting on the gauge-pulleys M, the movable frame A², saws and cutters I and I', lever-nuts D², screw feed-shaft L, and weights G², substantially as herein shown and described, for the purposes specified.

J. E. CROMWELL.
